FIG. 2.

FIG. 3.

INVENTOR

BENJAMIN F. CISOR
BY Hazard & Miller
ATT'YS.

UNITED STATES PATENT OFFICE.

BENJAMIN F. CISOR, OF LOS ANGELES, CALIFORNIA.

SANITARY-SEAT-SHIELD CUTTER.

1,320,602.

Specification of Letters Patent.

Patented Nov. 4, 1919.

Application filed February 12, 1919. Serial No. 276,692.

To all whom it may concern:

Be it known that I, BENJAMIN F. CISOR, a citizen of the United States, residing at Los Angeles, in the county of Los Angeles and 5 State of California, have invented new and useful Improvements in Sanitary-Seat-Shield Cutters, of which the following is a specification.

My object is to make a sanitary seat shield 10 cutter, and my invention consists of the novel features herein shown, described and claimed.

Figure 1 is a plan of a sanitary seat shield cutter embodying the principles of my invention.

Fig. 2 is a plan showing the cutter in operation.

Fig. 3 is a plan showing the sanitary seat shield prepared by the use of the cutter 20 shown in Fig. 1.

The sanitary seat shield cutter embodying the principles of my invention is preferably formed of sheet metal cut and stamped into shape. The straight edge 1 is simply a guide 25 and not a cutting edge. The curved inner edge 2 extending from the inner end of the straight edge 1 to the point 3 is a cutting edge, and the curve consists of the segmental end portion 4, the straight central portion 30 5, and the slightly curved end portion 6. In plan the portion 4 is concave relative to the body of the cutter, and the portion 6 is convex. The outer edge 7 is a cutting edge from the outer end of the straight edge 1 to 35 the point —D— near the point 3. The curved portion 8 of the outer edge is convex and eccentric to the inner edge portion 4. The end portion 9 of the outer edge 7 is substantially straight and the end portion 10 of 40 the outer edge 7 is substantially straight with a slight convex curve 11 at the extreme lower end. The body 12 is pressed upwardly from the edges 2 and 7, the high point being along the line 13 which is half 45 way between the cutting edges, so that the pressure downwardly upon the body 12 will press the cutting edges upon the material to be cut. A lip 14 is turned upwardly between the lower end of the outer cutting edge and the point 3 to serve as a non-cutting edge 50 and to serve as a handle.

In the practical operation of preparing a sanitary seat shield with the use of my cut-

ter a sheet of paper 15 is folded at its center thereby producing a folded straight edge 16, 55 and if desired two or three thicknesses of paper may be used; then the cutter is placed upon the folded paper with the straight edge 1 along the upper part of the straight edge 16 and the paper is torn or cut along the 60 inner cutting edge 2 from the lower end of the straight edge 1 to the point 3. The progress of this cutting operation should begin at the lower end of the straight edge 1 and continue downwardly along the cutting 65 edge 2 as indicated by the arrows —B—, said arrows and characters being formed upon the upper face of the cutter for guidance. The lines —A—A—, the arrows and characters —C— and the arrows and characters —D— are formed upon the upper face 70 of the cutter along the outer cutting edge for use in preparing directions for using the cutter.

After the paper has been torn to the point 75 3, the cutter is held upon the paper and the handle 14 manipulated to move the lower end of the cutter to the left in Fig. 2 until the outer cutting edge 7 intersects with the cut line 17 at the point —D—; then the paper is manipulated and the cutter held to tear or cut the paper along the outer cutting edge 7; and then the portion of the paper under the cutter may be removed or torn 80 away and the body of the paper 15 may be 85 unfolded and spread upon the toilet seat. The tongue 18 will hang downwardly at the front of the seat, and the remaining portion of the paper will cover the seat. The inner edge 19 will hang downwardly around the 90 edge of the opening. The cutter may be moved upon the paper to form an opening as desired, and to form various sizes of openings.

Various changes may be made without departing from the spirit of my invention as 95 claimed.

I claim:

1. A sanitary seat shield cutter formed of sheet metal cut and pressed into a shape 100 adapted for cutting a folded sheet of paper, a straight side for the cutter, to aline with the fold of the sheet of paper, having no cutting edge so that the paper may be cut and opened forming a properly shaped toilet 105 seat cover.

2. A sanitary seat shield cutter formed of sheet metal and having a straight edge forming a guide to align with the fold of the paper, the straight edge forming the guide 5 having no cutting edge, an inner curved cutting edge and an outer curved cutting edge, said cutting edges being adapted to bear

upon and cut a folded sheet of paper so that when the sheet of paper is opened a proper toilet seat cover is formed.

10

In testimony whereof I have signed my name to this specification.

BENJAMIN F. CISOR.
